(57) **CLAIM**

The ornamental design for a watch, as shown and described.

DESCRIPTION

FIG. 1 is a side perspective view of the first embodiment of the watches of the present invention.

FIG. 2 is a front perspective view of the watches embodiment of FIG. 1.

FIG. 3 is a first side view of the watches embodiment of FIG. 1.

FIG. 4 is a second side view of the watches embodiment of FIG. 1.

FIG. 5 is a side perspective view of the second embodiment of the watches of the present invention.

FIG. 6 is a front perspective view of the watches embodiment of FIG. 5.

FIG. 7 is a first side view of the watches embodiment of FIG. 5.

FIG. 8 is a second side view of the watches embodiment of FIG. 5.

FIG. 9 is a side perspective view of the third embodiment of the watches of the present invention.

FIG. 10 is a front perspective view of the watches embodiment of FIG. 9.

FIG. 11 is a first side view of the watches embodiment of FIG. 9; and,

FIG. 12 is a second side view of the watches embodiment of FIG. 9.

A brief description includes a watch with digital time display, in which the hours are represented by four LED's arranged parallel to each other horizontally, on which the hours are represented as a binary digit. There below, six LED's are arranged horizontally near each other, by which the minutes are displayed as a binary digit.
